UNITED STATES PATENT OFFICE.

JOHN T. TAVERNER, OF REDBANK, CALIFORNIA.

HAME-HOOK.

1,118,700.

Specification of Letters Patent. Patented Nov. 24, 1914.

Application filed August 8, 1913. Serial No. 783,711.

To all whom it may concern:

Be it known that I, JOHN T. TAVERNER, a citizen of the United States, and a resident of Redbank, in the county of Tehama and State of California, have invented a new and Improved Hame-Hook, of which the following is a full, clear, and exact description.

This invention relates to improvements in hame hooks, and has for an object to provide an improved structure which will prevent the traces from becoming accidentally disengaged when slack.

Another object of the invention is to provide a hook which will give a direct pull on the hame and which will not become entangled with a corresponding hook or other attachment when the horses crowd together.

In constructing a hook embodying the invention which carries out the objects above set forth a base plate is formed arranged of substantially any shape, preferably flat, with one end reduced and turned over for forming an eyelet designed to accommodate a staple or other securing means secured to the hame. The base has a hook arrangement formed integral therewith or rigidly secured thereto. This hook extends in the arc of a circle, and is provided at its free end with a return hook portion having a stop or lug, the return hook portion and stop or lug being arranged substantially in the same plane as the base. In order to accomplish this a portion of the base is cut out, whereby a link on a trace may be easily slid into position over the hook but will not become accidentally disengaged therefrom.

In the accompanying drawings—Figure 1 is a perspective view of a hook embodying the invention; Fig. 2 is a longitudinal horizontal vertical section through the structure shown in Fig. 1; Fig. 3 is a section similar to Fig. 2 but discloses a slightly modified form of the invention.

Referring to the accompanying drawings by numeral 1 indicates the body or base preferably formed with flat metal. At one end of the base a reduced extension 2 is provided which is bent over for forming an eyelet 3 through which a staple or other securing device is passed for securing the hook to a hame. Extending upwardly from the end of base 1, opposite extension 2, is a hook member 4 which extends in the arc of a

circle until the front end 5 thereof projects into a notched-out portion 6 of base 1. An auxiliary hooked portion 7 extends on end 5 and is provided with an enlargement or lug 8 which projects toward the hook member 4. The hook member 4 may be formed integral with base 1, as shown in Fig. 2, or if desired it could be made separately and rigidly secured in place. From Fig. 2 it will be observed that the hooked portion 7, together with part of the extension 8 and end 5 is arranged in substantially the same plane as base 1 and fits into notch or opening 6.

In operation when it is desired to connect a trace to the hook the link of the trace is passed through the front part of the opening 6 and is looped over the extension 8, after which the hame is moved back to its correct position so that the link will pull against the base of the hook member 4.

In Fig. 3 will be seen a slightly modified form of the invention in which the hooked extension 7' is rounded off at point 9 instead of being formed with a projection 8 similar to projection 8. Aside from these differences this structure is identical with the preferred form of the invention, and will therefore not need additional description.

Having thus described my invention what I claim as new and desire to secure by Letters Patent is—

1. In a hame hook of the class described, a base formed with an opening therein, with an extension at one end bent into an eyelet and an extension at the opposite end formed substantially arc-shaped so that the base, the free end of said hooked portion having a forwardly extending member on which an enlargement is provided, said forwardly extending member being arranged in the opening in said base but spaced therefrom and said enlargement projecting in a direction normal to said base.

2. In a hame hook of the class described, a base formed with a securing member at one end and a substantially arc-shaped hook member at the opposite end, said base being formed with an aperture, said arc-shaped hook member extending toward said aperture and arranged with its end projecting into said aperture, said end having a rearwardly extending portion projecting toward the base of the hook member and in the

same plane as said base, said rearwardly extending hooked portion being formed with a lug projecting in a direction normal to the base for preventing the accidental removal of a link or similar article placed in engagement with the hook member.

In testimony whereof I have signed my

name to this specification in the presence of two subscribing witnesses.

JOHN T. TAVERNER.
